UNITED STATES PATENT OFFICE.

CYRUS FRAILEY HURREL, OF HOLTON, KANSAS.

ENVELOPE OPENER.

Application filed May 27, 1922. Serial No. 564,094.

To all whom it may concern:

Be it known that I, CYRUS FRAILEY HURREL, a citizen of the United States, residing at Holton, in the county of Jackson and 5 State of Kansas, have invented new and useful Improvements in Envelope Openers, of which the following is a specification.

My present invention has reference to a 10 device for opening envelopes.

In carrying out my invention, it is my purpose to produce an extremely simple, cheaply constructed but thoroughly operative device whereby the edges of envelopes 15 may be severed in an easy and accurate manner.

It is a further object to produce a means 20 for clipping the edge of a sealed envelope which includes a base on which the envelope rests, a spring plate in the nature of a holder forcing the envelope against the base, stop means being provided on the base for properly positioning both the end and edge of the envelope, the last mentioned 25 means also serving as a guide for the movable knife of the device to properly position the cutting edge thereof with respect to the cutting edge of the stationery, the movable knife being operated by a suitable 30 handle.

A still further object is to produce an 35 opener for envelopes in which the edge of the envelope is severed and in which provision is made for taking care of such severed edges.

The foregoing, and other objects which 40 will present themselves as the nature of the invention is better understood, may be accomplished by a construction, combination and operative association of parts such as 45 is disclosed by the drawings which accompany and which form part of this application.

In the drawings:—

45 Figure 1 is a perspective view showing the manner in which an envelope is arranged on and severed by the improvement.

Figure 2 is a top plan view of the improvement.

50 Figure 3 is a sectional view on the line 3—3 of Figure 2.

Figure 4 is an edge view looking toward the cutting knives.

55 Figure 5 is a sectional view on the line 5—5 of Figure 4, showing the manner in which the pivoted cutting knife is limited

in its swinging movement and is guided toward the stationary knife, the said guide also serving as the means for limiting the outward movement of the envelope on the 60 device.

As disclosed by the drawings, I make use of a flat substantially rectangular base 1 which is preferably in the nature of a wooden block. On one edge of the base 65 1 secure a blade 2. The blade 2 extends the entire length of the base and the cutting edge thereof is beveled outwardly from the upper edge of the base. Passing through the blade and entering the base, 70 at points approximately equi-distant from the center thereof there are spaced hook-like members 3. These hooks serve as holding means for the edges which are clipped or cut from the envelopes. 75

Pivoted, as at 14 to the blade 2, adjacent one end thereof, and also if desired, to the base 1, there is the swinging blade 5. This blade has its lower edge preferably arranged at a curvature, its said lower edge 80 being beveled inwardly to provide the cutting edge which is indicated by the numeral 6. On its outer and reduced end the pivoted blade 5 is provided with an outwardly extending handle 7 whereby the 85 blade is operated.

Adjacent to the end thereof opposite that to which the pivoted blade 5 is pivoted, the fixed blade has arranged thereon an outwardly extending stop 8 which limits the 90 swinging of the pivoted blade over the fixed blade. Inward of the stop 8 there is secured upon the outer face of the fixed blade 2 an upwardly directed hook-shaped member 9. The beak 10 of the member 9 is rounded and 95 is disposed only a slight distance from the outer face of the fixed blade, being, however, arranged a slight distance above the cutting edge of the said fixed blade. The beak thus is arranged in a position to contact with the 100 outer edge of the envelope 11 when the same is arranged on the base, as illustrated in Figure 1 of the drawings, and therefore serves as a means for contacting with and holding the envelope to be engaged between 105 the fixed and pivoted knives.

Secured on the top of the base, and having its outer edge in a line with the inner face of the fixed blade 1 there is a flat spring member 12. The flat spring has, as stated, 110 only one of its ends secured to the base, and therefore its opposite end which is disposed

over the end of the base adjacent that provided with the stop and guide means is normally disposed above the base.

Passing through a suitable opening in the 5 spring member 12 there is a stop pin 13. In a line with this pin there is secured on the base a second stop pin 14. These pins are designed to be contacted by one end of the envelope 11 so that both the end and edge of 10 the envelope are maintained in proper position to be acted on by the cutting elements of the improvement.

It is thought that the foregoing description, when taken in connection with the 15 drawings will fully set forth the construction and operation of the improvement to those skilled in the art to which such inventions relate so that further detailed description will not be necessary. It is, of course, 20 to be understood that the spring member 12 is contacted by the finger of one hand of the operator when the envelope 11 is arranged on the device to be operated on by the cutting elements.

25 Having described the invention, I claim:—
1. In a device for the purpose set forth, a substantially rectangular block, a blade secured to one edge thereof having its upper edge beveled inwardly to provide a cutting 30 edge, a blade pivotally secured adjacent one end of the fixed blade having its lower edge curved and beveled inwardly to provide a cutting edge, an operating handle for the pivoted blade, stop means on the fixed blade 35 limiting the movement of the pivoted blade theretoward, spring means on the fixed blade

serving as a stop for an envelope arranged on the base and also serving to contact with and guide the pivoted blade toward the fixed blade, a spring plate having one end secured on the base disposed adjacent the fixed blade for contacting the envelope to compress the same against the base, and stop means on the base to engage one end of the envelope. 40 45

2. In an envelope opener, a substantially rectangular base, a blade secured to one edge thereof and having its upper edge beveled inwardly toward the base to provide a cutting edge, a blade pivotally secured adjacent 50 to one end of the fixed blade and having its lower edge curved and beveled to provide a cutting edge, an operating handle for the swingable blade, stop means on the fixed blade for limiting the movement of the 55 swingable toward the fixed blade, means on the fixed blade designed to contact with an envelope arranged on the base and to also contact with the swingable blade to guide the same toward the fixed blade, a spring 60 plate having one end secured on the base and arranged adjacent to the fixed blade and designed when contacted to compress an envelope arranged therebelow on the base, spaced stop means on the base for the envelope, one of which passing through the 65 spring plate, and spaced hook-like members projecting outwardly from the fixed blade to receive the severed portion of an envelope thereon. 70

In testimony whereof I affix my signature.
Cyrus Frailey Hurrel.
